UNITED STATES PATENT OFFICE.

HENRY P. CLAUSEN, OF CHICAGO, ILLINOIS, ASSIGNOR TO AMERICAN ELECTRIC TELEPHONE COMPANY, OF CHICAGO, ILLINOIS, A CORPORATION OF ILLINOIS.

TELEPHONE DESK SET.

SPECIFICATION forming part of Letters Patent No. 758,081, dated April 19, 1904.

Application filed May 26, 1902. Serial No. 108,946. (No model.)

To all whom it may concern:

Be it known that I, HENRY P. CLAUSEN, a citizen of the United States, and a resident of Chicago, in the county of Cook and State of Illinois, have invented a certain new and useful Improvement in Telephone Desk Sets, of which the following is a specification.

My invention relates to what are commonly known as "telephone desk sets." A device of this character usually consists of a transmitter and a receiver suitably supported and arranged upon a portable or movable support.

The particular form of telephone desk set to which my invention relates comprises a hollow standard adapted to inclose certain electrical connections and provided with a bottom portion, said bottom portion being preferably in the nature of a base adapted to rest upon a desk or table, the supporting structure thus formed having a transmitter and a receiver fork or lever mounted upon its upper portion and the said standard being of sufficient height to support the transmitter and receiver in suitably-elevated positions.

The objects of my invention are to provide a simple, compact, and efficient construction; to provide an improved construction in which the mounting for the contact-pieces, binding-posts, and connections can be readily removed from a tubular standard; to provide a telephone desk set so constructed that the different parts or members thereof may be held together by means of a single fastening device, such as a screw or bolt; to provide a simple and effective arrangement for limiting the swing of the transmitter; to generally simplify and reduce the number of parts; to reduce the cost of manufacture, and to provide certain details and features of improvement tending to increase the general efficiency of a device of this character.

To the foregoing and other useful ends, the desk set is preferably in the form of a standard provided with a suitable base and having a transmitter suitably mounted at its upper end. The said standard is preferably tubular in form and adapted to inclose the mounting which carries the contact-pieces and connec-

tions and to which is also pivoted the fork or lever which supports the receiver. The tubular standard has its lower end adapted to engage a socket in the base, and the upper end of said standard is adapted to engage the head or portion upon which the transmitter is mounted. This head is preferably secured to the upper end of the mounting, while the lower end of the latter is adapted to be engaged by the screw or like fastening device inserted through the bottom of the base. In this way the desk set comprises practically but three members, and with this arrangement these three parts or members are all held or secured firmly together by a single screw which extends upwardly through the base. With this construction and arrangement, the parts or members of the desk set can be readily taken apart, it being obvious that a loosening or removal of the screw from the bottom of the device will permit the base, standard, and head to be readily separated from each other. Furthermore, by thus simplifying the construction the cost of manufacture is greatly reduced. The nature and advantages of my invention will, however, herein-after more fully appear.

In the accompanying drawings, Figure 1 is a vertical section of a telephone desk set constructed in accordance with my invention, the transmitter and adjacent portion of the standard being in elevation. Fig. 2 is also a vertical section showing the transmitter and upper portion of the standard in elevation, the section in this case, however, being taken on a line at right angles to that of Fig. 1. Fig. 3 is a vertical section through the upper portion of the standard, showing the manner in which the receiver fork or lever is mounted upon the bar or member herein termed the "mounting." Fig. 4 is a view of the bottom of the base with the bottom plate removed. Fig. 5 is a horizontal section on line 5-5 of Fig. 1. Figs. 6 and 7 are enlarged detail views illustrating the two positions of the receiver fork or lever and illustrating the operation of the switch. Fig. 8 is an enlarged detail of the pivotal joint or connection between the trans-

mitter and the head. Fig. 9 is a horizontal section on line 9 9 of Fig. 8. Fig. 10 shows the mounting removed from the tubular standard, it being observed that said mounting is rigid with the head to which the transmitter is secured and it being also observed that in this view the upper and lower ends of said mounting are shown in vertical section. Fig. 11 is a vertical section of the tubular standard. Fig. 12 is a vertical section of the base upon which the tubular standard is mounted. Fig. 13 shows the screw which holds or binds together the base, standard, and mounting. Fig. 14 is a bottom view of the lower end of the mounting. Fig. 15 is a bottom view of the head upon which the transmitter is mounted. Fig. 16 is a section on line 16 16 in Fig. 10 looking in the direction indicated by the arrows. Figs. 17 and 18 are sectional views, respectively, of the bottom plate and rubber ring.

As thus illustrated the telephone desk set comprises a hollow or tubular standard A, a base or pedestal B, and a cap or head C. The lower end of said tubular standard is adapted to engage a seat or socket b in the base B. Said base is also preferably formed with a recess b', and, if desired, the base can be provided with a bottom plate b''. It will also be observed that said base is provided with a tube which provides a lateral opening b''. The said recess b', together with the opening b'' and recess b'', are designed to accommodate the telephone wires or connections which lead to the various binding-posts inclosed within the said standard A.

The core or mounting D, which carries the binding-posts 1, 2, 3, 4, 5, and 6, is preferably in the form of a flat or flattened bar extending substantially from the top to the bottom of the tubular standard A. Preferably the cap C is secured to the upper end of said mounting, and the lower end of the latter is provided with a round or disk-like portion d. This portion d is preferably provided with a threaded socket d', adapted to be engaged by the threaded upper end of the clamping-screw E. This screw, it will be observed, extends upwardly through the bottom of the base B and, as stated, has its upper end screwed into the threaded socket in the lower end of the mounting D. The pin e is preferably inserted through said screw, it being observed that said pin is inserted at a point above the lower or bottom wall of the recess b''. This pin serves to prevent end movement on the part of the clamping-screw E, and thereby permits the mounting D to be removed from the standard A without disengaging the screw E from the base B. In other words, the screw E with this arrangement maintains itself in position to engage the lower end of the said mounting and does not separate from the base when the members of the telephone set are taken apart. The cap or head C is adapted

to fit or rest upon the upper end of the tubular standard A. With this arrangement the screw E serves to draw and hold the three members together—that is to say, the arrangement enables this single clamping-screw E to 70 clamp the base, standard, and head tightly together. A tightening of this screw operates to draw the head secured to the mounting down in place upon the top of the standard and also operates to draw the tubular standard A down into place in the socket b. In order to insure the proper relative positions of the three members, the base is provided with a pin b'', inserted in such manner as to engage a notch a in the bottom of the standard, and also so as to engage a similar notch d'' in the periphery of the disk-like portion d. In assembling the proper relative positions can be obtained by relatively rotating the three members to an extent to bring the 85 notches a and d'' into engagement with the said pin b''.

As stated, the mounting D is designed and adapted to support the binding-posts, contact-pieces, &c., for the various electrical connections. This mounting is also adapted to support the fork or lever which supports the receiver and which operates the switch or means for throwing the bell in and out of circuit. As illustrated, this fork or lever F is preferably in the form of a bell-crank, it being provided with a downwardly-extending arm f. This lever is pivoted at f' and preferably arranged at the upper end of the mounting D. As a simple and effective arrangement the pivot for said fork or lever can consist of a screw f'', inserted through the lever and screwed into the mounting D. A flat spring f''' is arranged to hold the fork or lever normally in a raised or elevated position. Said spring is preferably secured at its lower end to the mounting D and has its upper end adapted to engage a notch in the lower end of the lever-arm f. A stop f'' is provided for limiting the downward swing of the fork or lever F. Arranged at either side of said spring are the contact-pieces G and H. These contact-pieces are preferably in the form of flat springs provided at their upper ends with insulating projections g and h. These insulating projections are adapted to engage opposite sides of the lever-arm f. The end of said lever-arm is provided at its opposite sides with small projections f'' and f''. When the lever is in its elevated or raised position, as shown in Figs. 1 and 6, the contact-piece G is in contact with the projection f''. When the lever is depressed, as shown in Fig. 7, the contact-piece H is brought into contact with the projection f'', and this downward movement of the fork or lever also operates to disengage the projection f'' from the contact-piece G. The spring f''' is, as stated, adapted to hold the fork or lever F normally raised; but it will be readily understood that 130

this spring is of such strength as to yield and permit the weight of the receiver to depress the lever and move it into the position shown in Fig. 7. The contact-pieces G and H, together with the fork or lever F, constitute a switch for throwing the bell into and out of circuit. When the lever is down, as shown in Fig. 7, the contact of the projection f^3 with the contact-piece H operates to throw the bell into circuit. When the receiver is removed and the lever allowed to rise, the bell is thrown out of circuit in the usual and well-known manner. The said fork or lever is arranged to swing in a notch or opening a' in the upper end of the tubular standard A. With further reference to the lower end portion of the mounting D it will be observed that the round or disk-like portion d is provided with a peripheral groove d^3 and also with a peripheral notch or recess d^4 . Said notch or recess d^4 is designed to afford an opening through which to lead the telephone-wires, which, it will be understood, are several in number, and these wires are preferably secured in place by a cord or wire wound around the peripheral groove d^3 .

The cap C, as stated, is secured to the upper end of the mounting D. This cap or head C is adapted to support the transmitter I, which, it will be understood, can be of any suitable known or approved form. Preferably, however, said transmitter has its back provided with a tongue i, adapted to fit between the cheeks or ears c, provided at the top of the cap or head C. The screw J is arranged to extend through said tongue and cheeks and is provided with a suitable nut j. By tightening said nut the cheeks or ears c can be compressed to an extent to squeeze the tongue i, thereby creating sufficient pressure and friction to hold the swinging transmitter in any desired position. In order to limit the swing of said transmitter, the tongue i is preferably provided with lateral projections or enlargements i', adapted to work or play in recesses c', formed on the inner surfaces of the cheeks or ears c. By referring to Fig. 8 it will be seen that these recesses c' are somewhat larger than the lateral projections or enlargements i' on the tongue i and that for this reason the transmitter is capable of a limited amount of vertical swing, the recesses c' and the projections i' constituting a stop arrangement for limiting such swing. It will be understood that the extent to which the transmitter is permitted to swing either up or down depends upon the relative formation of said recesses and projections.

With further reference to the spring f^3 and the contact-pieces G and H, constituting the switch device for throwing the bell in and out of circuit, it will be observed that the same are effectively and advantageously mounted in an insulating-block K, secured to the side of the mounting D by screws k. With this arrange-

ment the spring f^3 and flat contact-pieces G and H are held firmly in place and in position to be engaged by the lever-arm f. It will also be seen that the binding-posts 2 and 3 are preferably secured to the lower projecting ends of the contact-pieces G and H.

With reference to the wiring or electrical connection the cap or head C can be provided with an opening or passage c², communicating with a similar opening or passage i², extending through the tongue i and thence through the back of the transmitter. These openings or passages for the wire are shown in dotted lines in Fig. 8. With further reference to said electrical connections the circuits are shown diagrammatically in Fig. 1, and in this view the receiver L is shown in dotted lines.

In order that the set may not scratch or mar the desk, the plate b² can be employed for 85 clamping a rubber ring x in place upon the bottom of the base B. The said ring, as shown, is preferably wedge-shaped in cross-section, and the edge of the plate is correspondingly beveled.

From the foregoing it will now be seen that I provide a telephone desk set which is simple, compact, and efficient in construction and which is so constructed as to facilitate the assembling and taking apart of the different 95 portions of the device. It will also be seen that the arrangement and construction tends to reduce the cost of manufacture.

With the provision of the screw E the mounting D is adapted to act or serve as a tie-rod for binding the base and standard and other parts tightly together. In fact, the said screw and mounting may be said to combine to form a sort of tie-rod or member upon which a constant pull or tensile strain is exerted for the purpose of holding the parts together.

What I claim as my invention is—

1. A telephone desk set comprising a base, a transmitter, a mounting, a hollow standard mounted upon said base and inclosing said mounting, and a single clamping-screw inserted upwardly through said base and engaging the lower end of said mounting, said mounting thereby serving as a tie-rod to bind the different parts together.

2. A telephone desk set comprising a base, a mounting inclosed by a hollow or tubular standard, a transmitter and receiver fork or lever carried by said mounting, switch-springs inclosed by the standard and mounted on said mounting and operated by said fork or lever, and a fastening device applied to the base and the lower end of said mounting, the said mounting thereby serving as a tie-rod to bind the different parts together.

3. A telephone desk set comprising a base, a hollow standard, extending upwardly from said base, a mounting inclosed by said hollow standard, a transmitter and receiver fork or

- lever carried by said mounting, and a clamping-screw extending through the bottom of the said base and engaging the threaded opening in the lower end of said mounting, said 5 mounting being provided at its upper end with a head providing a shoulder, and the said screw being adapted and arranged for clamping the said standard between said base and the shoulder provided by said head.
- 10 4. A telephone desk set comprising a base, a hollow standard mounted upon said base, a mounting in the form of a bar extending vertically within said standard, the upper end of said bar being provided with a head providing a shoulder, a transmitter, a receiver fork or lever carried by said mounting, switch-springs mounted on said mounting and inclosed within the standard and operated by said receiver fork or lever, suitable binding- 15 posts also carried by said mounting, and a fastening device applied to the base and the lower end of said mounting, said fastening device constituting the sole means of clamping the said standard between the said head and base.
- 20 5. A telephone desk set comprising a suitable base, a standard mounted upon said base, a mounting, a transmitter, a receiver fork or lever carried by said mounting, switch-springs mounted upon said mounting and operated by 25 said lever, suitable binding-posts carried by said mounting, the upper end of said mounting being provided with a head, and a single clamping-screw applied to the said base and the lower end of said mounting, said screw 30 serving to clamp said standard between said base and head.
6. A telephone desk set comprising a base recessed to accommodate the telephone wires or cords, said base being also provided on its 35 top with a socket, a tubular standard mounted in said socket, a mounting inclosed by said tubular standard and having its lower end provided with a threaded opening, and a clamping-screw extending upwardly through the bottom of the base and engaging said threaded opening.
7. A telephone desk set comprising a base, a tubular standard mounted upon said base, a mounting in the form of a bar inclosed with- 40 in said tubular standard, the lower end of said bar being provided with a round or disk-like portion fitting the bore of said tubular standard and provided with a threaded socket, said mounting being provided at its upper end with a head, a transmitter pivoted to the upper end 45 of said head, a receiver fork or lever pivoted to said mounting at a point immediately below said head, binding-posts and suitable contact-pieces secured to the said mounting, and a clamping-screw extending through the bottom of said base and engaging the said threaded opening in said round or disk-like portion at the lower end of said mounting, said screw 55 serving to clamp said tubular standard between said base and head.
8. A telephone desk set comprising a suitable base, a tubular standard mounted thereon, a mounting inclosed by said standard and provided at its upper portion with a shoulder, a transmitter, a receiver fork or lever carried by said mounting, said receiver-fork being provided with a downwardly-extending arm, a flat spring secured to said mounting and having its upper end adapted to engage the lower end of said downwardly-extending lever-arm, 60 contact-pieces arranged to engage the opposite sides of said downwardly-extending lever-arm, suitable binding-posts secured to said mounting, and a fastening device applied to said base, and constituting the sole means of clamping said standard between said base and the shoulder on the upper portion of said mounting.
9. A telephone desk set comprising a suitable base, a tubular standard, a strip or bar 65 extending vertically in said standard, a transmitter and a hook-switch mounted upon the upper portion of said strip or bar, and a single fastening device applied to the lower end of said strip or bar, the said strip or bar thereby serving as a tie-rod to bind the different parts together.
10. A telephone desk set comprising a suitable base provided with a tubular standard, a mounting inclosed by said tubular standard, a 70 switching device carried by said mounting and adapted to support a telephone-receiver, a transmitter also carried by said mounting, and a single fastening-screw inserted upwardly through the base and engaging the lower end of said mounting.
11. A telephone desk set, comprising a base provided with a hollow standard, a removable mounting inclosed by said standard, switch-springs carried by said mounting, a switch-hook carried by said mounting and adapted to operate said springs, said switch-hook being adapted to support a telephone-receiver, a transmitter carried by said mounting, and a single screw-threaded member constituting 75 the sole means for maintaining the said mounting in its proper position relative to the base and standard.
12. In a telephone desk set, the combination of a base, a tubular standard mounted thereon, a mounting inclosed by said tubular standard and provided at its upper portion with a shoulder, a transmitter, a receiver fork or lever carried by said mounting, a clamping-screw extending upwardly through said base 80 and engaging a threaded opening in the lower end of said mounting, and a pin extending through said clamping-screw and adapted to prevent end movement on the part of the latter relatively to said base, said screw serving 85 to clamp the said standard between the said base and the shoulder on the upper end of said mounting.
13. In a telephone desk set, the combination of a plurality of members forming a structure 90

for supporting a transmitter and a receiver fork or lever in a suitably-elevated position, and a single clamping-screw applied to the bottom of the said structure, and constituting 5 the sole means of drawing and holding said members tightly together.

14. A desk telephone comprising a core having a head, a switch-hook mounted on the core, a transmitter mounted on the head, a 10 base, a tube inclosing said core, and fastening means including said core for clamping said tube endwise between said head and base.

15. The combination of an upright structure, a transmitter and receiver hook mounted thereon, a base upon which the structure is mounted, a rubber ring wedge-shaped in cross-section, and a plate having a beveled edge for clamping the ring to the bottom of said base; and means for holding the different parts together, 20 said means including a mounting and a screw, said mounting, when the screw is tightened, serving as a tie-rod to bind the parts together.

16. A telephone desk set, comprising a base, 25 a hollow standard having its lower end removably mounted on said base, a mounting in said standard, a transmitter and a hook-switch carried by said mounting, and a screw for hold-

ing the base, standard and mounting firmly together, said screw extending upwardly 30 through the base and engaging the lower end portion of the mounting, whereby the said screw is readily accessible from below.

17. A telephone desk set comprising a suitable base, a tubular standard having its lower 35 end removably mounted on said base, a strip or bar extending vertically in said standard, a transmitter and a hook-switch mounted upon the upper portion of said strip or bar, and a single screw-threaded fastening device applied 40 to the lower end of said strip or bar, the said strip or bar thereby serving as a tie-rod to bind the different parts together.

18. A telephone desk set provided with a hollow base, and provided also with a removable bottom plate having a beveled edge, together with a cushioning-ring encircling said plate and held in place by the beveled edge of the latter.

Signed by me at Chicago, Cook county, Illinois, this 22d day of May, 1902. 50

HENRY P. CLAUSEN.
